COAL DEVOLATILIZER

Andrew F. Howe, University City, Mo., assignor to
 Centrifugal & Mechanical Industries, Inc., St.
 Louis, Mo., a corporation of Missouri.

Application June 15, 1944, Serial No. 540,512

7 Claims. (Cl. 202—26)

1

This invention relates to devolatilization of coal; and it has special reference to a method and apparatus for reducing the volatile in coal so that slurry coal or small bodies of coal that will pass through a screen having a relatively fine mesh may be readily formed into combustible briquettes and nearly all of the combustible gases burnt during combustion of the briquettes.

An object of the invention is to provide a method and apparatus for removing the volatile from slurry coal and from quantities of small bodies of coal by carrying the same through a heated oven by a constantly moving conveyor so that most or a desired amount of the volatile content of the coal will be detached and separated therefrom, withdrawing the separated volatile content from the oven during movement of the coal therethrough, and then forming the substantially devolatilized coal into briquettes or other substantially solid bodies convenient for handling, transportation, and combustion.

Another object of the invention is to provide an apparatus for separating a desired amount of the volatile content from slurry coal and from quantities of small bodies of coal by the application of heat generated by a combustion device using and burning the separated volatile content of the coal, or using and burning other fuel or using and burning both said separated volatile content and said other fuel, as desired, and means for forming the substantially devolatilized coal into solid bodies or briquettes that may be conveniently handled and which will readily burn without discharging objectionable quantities of obnoxious smoke, fumes, and gases.

Another object of the invention is to provide an improved method for reducing the volatile content in slurry coal or small bodies of coal by passing or conveying said coal into, through and from a heated oven at a selected rate of speed, withdrawing from said oven the volatile content emanating from the coal therein and thereby creating or forming a partial vacuum in said oven, supplying fresh air into said oven to replace or replenish the volatile content that emanates from the coal therein and which is withdrawn therefrom, and discharging the coal in any form desired after it has passed from said oven.

Other objects will appear from the following description, reference being made to the annexed drawings, in which—

Fig. 1 is a plan view showing one form of an apparatus for practicing the present invention of substantially reducing the volatile content of

2

slurry coal or quantities of small bodies of coal regardless of whether the coal is formed into briquettes or bodies for combustion, or is not so formed.

5 Fig. 2 is a vertical longitudinal sectional view of an apparatus for reducing the volatile content of slurry coal or of quantities of small bodies of coal, and also forming the devolatilized coal into briquettes or solid bodies.

10 Fig. 3 is an enlarged sectional view of a portion of the conveyor for the slurry coal or small particles of coal and of one form of device for shaping the coal into solid bodies or briquettes.

15 Fig. 4 is a still further enlarged sectional view of a portion of the device that shapes the coal into solid bodies or briquettes.

Fig. 5 is a plan view of a portion of said device.

20 Fig. 6 is a perspective view of a solid body or briquette of devolatilized slurry coal made by the apparatus of the present invention.

Fig. 7 is a vertical cross-sectional view on the line 7—7 of Fig. 1.

Fig. 8 is a side elevation of the apparatus shown in Fig. 1.

25 Fig. 9 is a sectional view of a portion of an apparatus for forming the devolatilized coal into solid bodies or briquettes.

Fig. 10 is an enlarged side elevation of one of the cutting rolls shown in Fig. 9.

30 Fig. 11 is a similarly enlarged side elevation of a portion of a cooperating cutting roll.

Fig. 12 is a perspective view of another form or shape of a solid body or briquette of devolatilized coal formed by the rolls shown in Figs. 10 and 11.

35 Fig. 13 is a vertical longitudinal sectional view of an apparatus for practicing the invention by the use of fuel gas only.

The apparatus shown for removing volatile

40 from slurry coal or from quantities of small bodies of coal comprises a furnace having refractory enclosing walls 1. This apparatus is an embodiment of an idea of means comprising part of the invention for successfully practicing the method portion of the invention. If desired, the furnace may be divided into at least two combustion chambers or fire-boxes 2 by a partition 3, also preferably composed of refractory material.

45 Each combustion chamber of the furnace may enclose a chain grate stoker 4 of known construction and action mounted at one side of the furnace on a rotative operating or driving roll 5 and, at the opposite side of the furnace, on a rotative supporting roll 6. The rolls 5 and 6 are preferably of the same diameter and rotate about

horizontal axes in the same horizontal plane. In the modification of the apparatus shown, there are two combustion chambers 2 each having therein a chain grate stoker 4 and having the driving rolls for said respective chain grate stokers mounted at opposite sides of the furnace. Within the furnace, the ends of the chain grate stokers 4 operate on and along supporting rails 7. Each driving roll 5 may be rotated intermittently or continuously as desired by operating mechanism provided for that purpose. As shown, an electric motor 8 is operatively connected with the shaft 9 of each operating roll 5 by suitable speed reducing gearing 10. Any known type of connection from the motor 8 to the shaft 9 of each driving roll 5 may be employed. Solid fuel such as coal may be fed onto the end of each grate 4 above or adjacent to the driving roll 5 through a hopper 11. The hoppers 11 extend the full width of the respective chain grate stokers 4, and will discharge the coal onto said grate stokers for movement into the furnace. The two grates shown move in opposite directions across the furnace through the respective chambers 2, from which the burnt gases, smoke, and like products of combustion are conducted and pass through flues 12. One of the flues 12 opens from each combustion chamber 2 at the opposite side of the furnace from the stoker hoppers 11. Each combustion chamber 2 is provided with a cover 13 preferably of metal and which may be of arch formation and which prevents ignition and combustion of a slurry coal or quantities of small bodies of coal conveyed through the oven 14 above the furnace.

The oven 14 is wholly out of communication with the combustion chambers 2 and is covered by a top wall 15 which may be composed of the same refractory material forming the walls 1 and 3, or of other appropriate material as desired. An elongated horizontal inlet opening 16 is formed through one of the walls 1 of the furnace above the cover 13, and a complementary horizontal outlet opening 17 is formed through the opposite wall 1 of the furnace. The conveyor for the slurry coal or quantities of small bodies of coal passes through the opening 16 into the oven 14 and passes from said oven through the opposite complementary opening 17. The conveyor itself is of novel construction, comprising at least two endless series of pivotally connected links 18 forming endless chains engaged with two axially aligned sprocket wheels 19 attached to a rotary actuator shaft 20 beyond the outlet opening 17. The sprocket chains 18 engage similar sprocket wheels 21, 22 and 23 attached to shafts 24, 25 and 26, respectively. All of the shafts 20, 24, 25 and 26 extend horizontally and parallel with each other. It is evident that, when the shaft 20 is rotated in a counter-clockwise direction, as indicated by the arrow 27 (Fig. 2), the sprocket wheels 19 will be rotated in the same direction and will thereby move both or all of the sprocket chains 18 in the direction of the arrow 28.

The complementary links 18 on the respective chains support pans each comprising a bottom wall 29 extending the full distance between the two side chains 18, and two end walls 30. The height of the side walls 30 of the pans is less than the vertical width of the openings 16 and 17 into and from the oven 14, so that the conveyor comprising the sprocket chains 18 and the pans 29-30 may pass freely through said openings. The pair of shafts 20 and 24 and the complementary pair of shafts 25 and 26 are beyond opposite

ends of the furnace. The shaft 20 may be constantly or intermittently rotated by connections 31 operated by an electric motor 32 through suitable speed reducing gearing (not shown). Between the sprocket wheels 23 and 19 the chains 18 operate along and are supported by rigid rails 33 which support the upper stretch of the conveyor in a straight horizontal plane and prevent sagging thereof. If desired, the intermediate portion of the conveyor bottom walls 29 between the chains 18 may be supported by any appropriate device. It will be noted in Fig. 2 that the bottom walls 29 of the conveyor pans 29-30 are close to the covers 13 which form the bottom wall of the oven 14 through which the coal is carried by the conveyor and subjected to heat emanating from the furnace.

The slurry coal or quantities of small bodies of coal are delivered onto the upper stretch of the conveyor comprising the pans 29-30. The coal is delivered in controlled quantities through a chute 34 having a discharge opening 35 at its lower end extending nearly the full width of the conveyor between the side walls 30 of the pivotally connected conveyor pans. The walls of the chute 34 forming the discharge opening 35 terminate immediately above the side walls 30 of the conveyor pans and do not interfere with the free movement and operation of said conveyor. A hopper 35 for containing the slurry coal or quantities of small bodies of coal to be processed by this invention opens into the upper end of the chute 34. Measured quantities of slurry coal or of the small bodies of coal contained in the hopper 35 are moved from said hopper and discharged into the chute 34 automatically and as an incident to operation of the apparatus. A rotary shaft 36 extends horizontally across the communication from the hopper 35 to the chute 34 concentrically with opposite portions 37 and 38 of the walls connecting said hopper with said chute. The shaft 36 is rotated by driving connections from the motor 8. A pair of circular end walls 39 are attached to the shaft 36 and are connected by walls 40 extending radially from the shaft 36 and cooperating with the walls 39 to form measuring compartments 41. Each measuring compartment 41 will receive and move a quantity of slurry coal or small bodies of coal from the hopper 35 during rotation of the measuring device and successively discharge said quantities into the chute 34 from which the coal moves by gravity onto the conveyor. The shaft 36 is rotated by a connection 36' operated by the rotary conveyor shaft 26 only when the conveyor is operated by the shaft 20 (Fig. 8).

A pipe 42 opens through the top wall 15 of the oven 14 and constitutes an outlet passage for withdrawing gases and volatile liberated from the coal in and passing through the oven 14. A vacuum pump 43 operated by connections 44 driven by a motor 45 is connected to the effluent end of the passage 42 and functions to withdraw gases and volatile from the oven and form or create a partial vacuum therein. The oven 14 is air tight, and receives no outside air except through the openings 16 and 17. This feature substantially aids the emanation and withdrawal of volatile content from the coal within the oven. From the vacuum pump 43, a pipe 46 conducts the gases and volatile into a tank 47 which may be located in any place desired and which is shown between one of the walls 1 of the furnace and the adjacent pair of shafts 20 and 24. A pipe 48 opens from the inside of the upper end of the tank 47

and has stretches or extensions 49 across each combustion chamber 2 substantially above the stoker grates 4 and below the covers 13 of the respective combustion chambers 2. The stretches or extensions 49 are provided with numerous gas outlet openings 50 for discharging gas into the combustion chambers for mixture with the gases and fumes rising from the burning coal on the stoker grates, and thus burning said gases constantly during operation of the apparatus. By making 10 the areas of the holes 50 of proper size, they will control the pressure of the gases pumped therethrough and dispense with the necessity of using valves or the like in connection with the pipe 48 of the extensions 49.

Two parallel horizontal shafts 51 and 52 are supported for rotation above the conveyor 29-30 adjacent to and beyond the outlet opening 17 from the oven 14 and between the furnace wall 1 and the vertical plane or discharge end of the shaft 20. A pair of sprocket wheels 53 is attached to each of said shafts 51 and 52. An endless device for forming the devolatilized coal into solid bodies or briquettes is engaged upon the sprocket wheels 53. Said device comprises a series of pivotally connected transversely elongated links 54 in which are formed molds or cutters 55 for cutting and compressing the layer of substantially devolatilized sheet of slurry coal or sheet of small bodies of coal spread upon the conveyor bottom walls 29 and which had been carried thereby through the heated oven 14. The molds or cutters 55 cut and compress the substantially devolatilized layer of coal into solid bodies or briquettes 56 (Fig. 6), leaving said solid bodies or briquettes 56 on the conveyor for discharge therefrom beyond the shaft 20. One of the shafts 51 or 52 may be rotated by the connections 31 operated by the motor 32 for rotating the shaft 29 (Fig. 8), or otherwise as desired. Thus, the conveyor and the briquetting device may be concurrently operated.

From the conveyor 29-30, the briquettes are discharged into a chute 57 and conducted to a rotary discharge device comprising a shaft 58 attached to circular end walls 59 connected by walls 60 extending radially from the shaft 58. The shaft 58 is rotated by connections 58' operated by the motor 32. The walls 59-60 form compartments 61 which receive quantities of briquettes from the chute 57 and deliver them into a discharge chute 62. Any particles of coal adhering to the conveyor may be detached therefrom by a brush 63 (Fig. 2) supported and operated by a rotary shaft 64 below the plane of the shaft 20. The brush 63 may be rotated in the direction of the arrow 65 (Fig. 2) and thereby impel and cause the detached particles of coal to drop by gravity into a space 66 from which they may be removed and replaced, or otherwise disposed of as desired.

The end of each combustion chamber 2 opposite from the fuel feed hopper 11 and driving roll 5 discharges the ashes and waste remnants of the burnt coal into a closed ashpit 67. Above each ashpit 67, the ends of the combustion chambers 2 are provided with clean-out doors 68 which are closed during operation of the apparatus and which may be opened to permit the respective combustion chambers to be cleaned by removal of solids therefrom. Beyond the ends of the furnace, enclosing walls 69 extend. At one end the chute 34 opens through the top of the enclosing wall 69 which encloses the mechanism comprising the shafts 25, 26, adjusting devices 70 75 78. Additional quantities of either natural or

for the shaft 25, etc. At the opposite end the mechanism comprising the shafts 20, 24, the briquetting device, the mechanism 58-59-60, and the brush 63-64, are enclosed in a compartment formed by said enclosing wall 69.

Air may be admitted into the space enclosed by the walls 19 and thence into the oven 14 in order to prevent formation of excessive vacuum therein by operation of the vacuum pump 43 which withdraws gases and air from the oven 14 through the pipe 42. An air inlet device 71 opens into one end of said space which is enclosed by the walls 69 and functions to admit air into said space and thence into the oven 14 through the openings 16 and 17. Thus, the air in the oven is replenished and formation of excessive vacuum therein is prevented.

By the modification shown in Figs. 9, 10 and 11, the devolatilized coal on the conveyor 29-30 may be compressed and cut into solid bodies or briquettes 72 (Fig. 12) otherwise than by the device shown in Figs. 3, 4 and 5. In substitution for said device, the said mechanism shown in Figs. 9, 10 and 11 may be used for compressing, shaping and cutting the coal on the conveyor 29-30 into solid bodies or briquettes. An endless presser device 73 is mounted on the sprocket wheels 53 in substitution for the endless cutter 54-55, and is formed with a smooth outer surface instead of the molds or cutters 55. The presser device operates in the same manner as the endless device 54 which contains the molds or cutters 55 and functions to compress, smooth and flatten the devolatilized coal on the conveyor 29-30. Forwardly beyond the presser device 73 a roller 74 extends parallel with the upper surface of the conveyor 29-30 and has numerous circumferential and longitudinally spaced cutting knives or flanges 75 which cut the compacted devolatilized coal into parallel longitudinal strips during movement of the conveyor 29-30 under the said roller 74. Adjacent to the roller 74 another roller 76 having numerous longitudinal cutting knives or flanges 77 is arranged to cut transversely the pressed devolatilized coal that had been cut into parallel longitudinal strips by the circumferential flanges or cutters 75. The roller 74 with its circumferential flanges or cutters 75 and the roller 76 with its longitudinal flanges or cutters 77 cut the pressed devolatilized coal into said solid bodies or briquettes 72 which are discharged or dropped from the conveyor 29-30 into the hopper 57, as do the solid bodies or briquettes 56. The relative positions of the rollers 74 and 76 may be reversed, and they may be positively driven or freely rotative if desired.

The modification shown in Fig. 13 is designed for the exclusive use of gas as a fuel within the combustion chambers. That is, from the said modification of the invention shown in Fig. 13, the coal stoker grates 4, motors 8 and connections therefrom for operating said stoker grates, the ashpits 67 for receiving ashes and solid refuse from the combustion chambers 2, and other parts required when coal is used as a fuel and that are not required when gas alone is used as a fuel, are omitted. In this form of the invention, the vertical height of the combustion chambers 78 is considerably less than the vertical height of the combustion chambers 2 to which they are otherwise analogous. From the stretches or extensions 49 of the gas conduit pipe 48, numerous gas burners 79 receive gas and extend toward the metallic covers 13 for said combustion chambers 70 75 78. Additional quantities of either natural or

manufactured gas may be supplied into the tank 47 or directly to the pipe 48 or stretches 49 through a pipe 80, so that a constant supply of a sufficient amount of gas is always delivered and supplied to the burners 79 when the apparatus is in use. Necessary air may be admitted into the combustion chambers 78 through openings 81 provided for that purpose. In other particulars, the construction and form of the apparatus shown in Fig. 13 is the same as that already described and as shown in Fig. 2, and like reference numerals are applied to the same parts.

From the foregoing disclosure, it is evident that this invention produces solid bodies or briquettes of devolatilized coal ready for satisfactory use as substantially "smokeless" fuel. The approximate temperatures to which the coal must be subjected while the coal is within the oven 14 or during movement of the coal through said oven may be predetermined and the apparatus may be regulated to supply said required temperatures. The speed of continuous or intermittent movement of the coal through the oven 14 may be regulated as desired by controlling the speed of continuous or intermittent operation of the motor 32 and the connections therefrom for rotating the shaft 20 and moving the conveyor continuously or intermittently. The apparatus specifically disclosed is for processing slurry coal to lower the volatile thereof to any extent desired, and such volatile may be used and consumed as fuel in the combustion chambers that supply heat for devolatilizing or lowering the volatile content of the coal.

The invention may be varied in equivalent particulars other than those specifically shown and described without departure from the nature and principle thereof.

I claim:

1. The method of reducing the volatile content of slurry coal, which consists in depositing a layer of slurry coal upon a moving conveyor, moving said conveyor and the layer of loose and unpressed slurry coal thereon into and through a heated oven containing only air and the volatile and gases emanating from said coal, withdrawing said air and said volatile and gases emanating from said coal during movement of said coal through said oven, and compressing and applying pressure to form said layer of coal into solid bodies or briquettes after said layer has been moved through said oven by said conveyor.

2. The method of reducing the volatile content of slurry coal or of quantities of small bodies of coal, which consists in depositing a loose and unpressed layer of said coal upon a moving conveyor, moving said conveyor and said loose and unpressed layer of said coal thereon into and through a heated oven containing only air and the volatile and gases emanating from said coal, and creating and forming a partial vacuum in and withdrawing said air and said volatile and gases emanating from said coal in said oven during movement of said coal through said oven.

3. The method of reducing the volatile content of slurry coal or of quantities of small bodies of coal, which consists in depositing a loose and unpressed layer of said coal upon a moving conveyor, moving said conveyor and said loose and unpressed layer of said coal thereon into and through a heated oven containing only air and the volatile and gases emanating from said coal, creating and forming a partial vacuum in and withdrawing said air and said volatile and gases emanating from said coal in said oven during

movement of said coal through said oven, and compressing said coal flatwise on said conveyor only after said coal has been moved out of said oven.

5. An apparatus for reducing the volatile content of a loose and unpressed layer of slurry coal and small bodies of coal, comprising walls forming and enclosing an oven and including two opposite walls having elongated horizontal openings therethrough near the bottom of said oven, said walls also forming and enclosing a combustion chamber below said oven for heating the same, an impervious metallic cover for said combustion chamber forming the bottom wall of said oven and supported by and cooperating with said first walls to seal said oven from said combustion chamber and also to heat said oven, a series of four parallel shafts outside of said oven and said combustion chamber, an endless conveyor supported by said shafts and extending through said oven and through said openings adjacent to said cover for receiving and moving through said oven said loose and unpressed layer of said coal, other walls forming two compartments enclosing said shafts wholly out of communication with said oven, a measuring device operated by one of said shafts for delivering a layer of measured quantities of said coal onto said conveyor in one of said compartments adjacent to said one shaft, a tank enclosed in the other one of said compartments, means forming a passage for conducting from said oven into said tank volatile content emanating from said coal in said oven, and a burner in said combustion chamber having connections communicating with said tank for burning said volatile content and heating said oven.

40. 5. An apparatus for reducing the volatile content of a loose and unpressed layer of slurry coal and small bodies of coal, comprising walls forming and enclosing an oven and including two opposite walls having elongated horizontal openings therethrough near the bottom of said oven, said walls also forming and enclosing a combustion chamber below said oven for heating the same, an impervious metallic cover for said combustion chamber forming the bottom wall of said oven and supported by and cooperating with said first walls to seal said oven from said combustion chamber and also to heat said oven, an endless conveyor extending through said oven and through said openings adjacent to said cover for receiving and moving through said oven said loose and unpressed layer of said coal, mechanism for moving said conveyor and thereby said layer of loose and unpressed coal through said oven and discharging said coal therefrom, other walls forming two compartments enclosing portions of said conveyor beyond said oven, a measuring device operated by said mechanism for delivering a layer of measured quantities of said coal onto said conveyor in one of said compartments, a tank enclosed in the other one of said compartments, a burner in said combustion chamber, and means for conducting from said tank to said burner volatile content emanating from said coal in said oven.

65. 6. An apparatus for reducing the volatile content of a loose and unpressed layer of slurry coal and small bodies of coal, comprising walls forming and enclosing an oven and including two opposite walls having elongated horizontal openings therethrough near the bottom of said oven, said walls also forming and enclosing a combustion chamber below said oven for heating the same, an impervious metallic cover for said com-

bustion chamber forming the bottom wall of said oven and supported by and cooperating with said first walls to seal said oven from said combustion chamber and also to heat said oven, an endless conveyor extending through said oven and through said openings adjacent to said cover for receiving and moving through said oven said loose and unpressed layer of said coal, mechanism for moving said conveyor and thereby said layer of loose and unpressed coal through said oven and discharging said coal therefrom, other walls forming two compartments enclosing portions of said conveyor beyond said oven, a measuring device operated by said mechanism for delivering a layer of measured quantities of said coal onto said conveyor in one of said compartments, a burner in said combustion chamber, and means forming a passage for conducting from said oven to said burner the volatile combustible content emanating from said coal in said oven.

7. An apparatus for reducing the volatile content of a loose and unpressed layer of slurry coal and small bodies of coal, comprising walls forming and enclosing an oven and including two opposite walls having elongated horizontal open-

25

ings therethrough near the bottom of said oven, said walls also forming and enclosing a combustion chamber below said oven for heating the same, an impervious metallic cover for said combustion chamber forming the bottom wall of said oven and supported by and cooperating with said first walls to seal said oven from said combustion chamber and also to heat said oven, an endless conveyor extending through said oven and through said openings adjacent to said cover for receiving and moving through said oven said loose and unpressed layer of said coal, mechanism for moving said conveyor and thereby said layer of loose and unpressed coal through said oven and discharging said coal therefrom, other walls forming two compartments enclosing portions of said conveyor beyond said oven, a measuring device operated by said mechanism for delivering a layer of measured quantities of said coal onto said conveyor in one of said compartments, and mechanism in the other one of said compartments for pressing and compacting said coal into separate combustible briquettes.

ANDREW F. HOWE.
